UNITED STATES PATENT OFFICE

124,024

DESIGN FOR A GAME BOARD

Charles Webb Godefroy, University City, Mo.

Application September 18, 1940, Serial No. 95,185

Term of patent 14 years

To all whom it may concern:

Be it known that I, Charles Webb Godefroy, a citizen of the United States and a resident of University City, in the county of St. Louis and State of Missouri, have invented a new, original, and ornamental Design for a Game Board, of which the following is a specification, reference being had to the accompanying drawing, forming part thereof.

Fig. 1 is a plan view of a game board embodying my design.

Fig. 2 is an edge view of said board.

I claim:

The ornamental design for a game board, as shown.

CHARLES WEBB GODEFROY.
